PLUNGER-TYPE CURRENT INTERRUPTER

Herbert L. Rawlins, Wilkinsburg, Pa., assignor
to Westinghouse Electric & Manufacturing
Company, a corporation of Pennsylvania

Application April 15, 1932, Serial No. 605,398
Renewed October 16, 1935

16 Claims. (CL. 200—120)

My invention relates to current-interrupting devices and particularly to devices of the type in which the arc is extinguished by means of a blast of non-ionized gas or vapor.

5 This application covers a further development of the circuit interrupter disclosed in application Serial No. 568,554, filed October 13, 1931 by Joseph Slepian.

It is an object of my invention to provide a 10 device of the class described which shall be adapted to interrupt arcs over a greater range of current values than has heretofore been possible.

It is a further object of my invention to provide 15 a current interrupter of the type employing a movable contact member with cooperating gas-generating means and to so select the speed of movement that sufficient gas pressure to burst the device will not be developed at any currents at which the device is expected to operate.

20 It is a further object of my invention to provide a body of arc-responsive material with a passage therethrough of a varying diameter so arranged that the large cross-section shall be in the proper 25 position to take part in the extinguishing of arcs of large current and the smaller cross-section will be active only when arcs of smaller current are being extinguished.

It is a further object of my invention to insure 30 that the movable member shall not travel into the portion of the passage having a small cross-section before sufficient time has elapsed for the extinguishing of an arc of large current value.

It is a further object of my invention to provide 35 a current interrupter, of the type producing a gas blast, particularly adapted for use in alternating current circuits and in which the gas pressure shall never greatly exceed the pressure developed during the first half-cycle by the heaviest arc for which the device is intended.

40 I produce these results by providing a plunger type of circuit interrupter in which the plunger travels through a passage lined with boric acid or other arc-responsive material. The passage is provided with a bell-shaped mouth adjacent 45 the starting point of the arc and the movable electrode traveling through the passage elongates the arc. This brings the arc into the small part of the passage when it lasts long enough to endure through such a movement of the plunger. This 50 can occur only at small currents because at heavy currents sufficient gas is generated to extinguish the arc while the plunger is still within the bell.

I provide a sufficient inertia in the plunger to 55 insure that its motion will be slow enough to

avoid elongating a heavy-current arc into the small part of the passage and thus avoid the development of heavy gas pressures.

Other objects of my invention will be manifest and a better understanding of the details of construction will be obtained by reference to the following detailed description and the accompanying drawing, in which

Figure 1 is a longitudinal sectional view of one form of my device.

Fig. 2 is a view partly in section and partly in side elevation illustrating another form thereof.

Fig. 3 is a similar view illustrating a third form.

Referring to Fig. 1, a cylindrical tube 1 of fibre or other insulating material is provided at its 15 lower end with a metallic cap 2 adapted to cooperate with clips or other devices at one terminal of the circuit with which the current interrupter is to cooperate. The other end of the tube 1 is provided with a metal sleeve 3 which may serve 20 for connection to the other terminal of the circuit directly or by means of a metallic prolongation 4.

A metallic washer 5 is connected to the cap 2 in any convenient or suitable manner. In the 25 construction which I have chosen for illustration, the metallic lining 6 affords this connection.

Bearing against the washer 5 and filling the tube from this washer to the junction with the sleeve 3, I provide a body 7 of material which, 30 when exposed to an arc, will evolve a gas, vapor or other emanation capable of acting upon the arc to increase the time rate of deionization.

This lining may be provided by compressing boric acid with a pressure of 5 to 15 tons per 35 square inch in suitable moulds to form blocks or briquettes of a size to fit the tube 1. The briquettes are moulded with a central opening to provide the passage 8, which extends through the whole body of boric acid. Instead of boric acid, alternate discs of hard fibre and fullerboard discs may be provided. The fullerboard is somewhat more effective if soaked in oil but the device is not then as permanent. Other substances which can be used are borax, aluminum 40 borate, compressed naphthalene, salicyclic acid and silicic acid. Boric acid is a most desirable material since when acted upon by the arc it gives off water vapor which is non-inflammable and readily condensed.

A plunger 11 is located in the passage 8 and is secured at one end to the sleeve 3 by a fusible link 12 having a reduced section which melts initially. The plunger fits the passage as closely as may be without friction. This is much closer than 50

illustrated in the drawing. The link is soldered or otherwise secured to the adjacent end of the plunger 11 and is attached to a flange 9 extending inwardly from the sleeve 3 by any suitable mechanical fastening such as the screw 13. The opposite end of the plunger 11 is attached to a disk 14 which serves as one abutment for a spring 15, which bears against the washer 5 either directly or through an in-turned flange of the sleeve 6. Flexible connectors 16 extend from the flange 14 to the sleeve 6 and thus afford connection between the plunger 11 and the cap 2 in all positions of the plunger 11.

The extension 4 mounted upon the sleeve 3 contains copper washers 17 alternating with metallic spacing rings 18, the pile of alternating rings being secured together and fastened within the extension 4 by bolts 19 which also secure the extension 4 to the sleeve 3 and secure a cap ring 20 in place at the end of the extension 4. The cap ring may be provided with a central opening through which gases can escape or this opening may be closed by a stopper 21 as illustrated in the drawing.

In Fig. 2 the construction is similar to that illustrated in Fig. 1 but a different means is provided in place of the fusible member 12 for opening the circuit. Two contact springs 22 are mounted upon the flange 9 of the sleeve 3 and the plunger 11 in its normal position extends between the contact springs 22 and is thereby electrically connected to the sleeve 3. A weight 23 at the lower end of the plunger 11 moves the plunger downwardly when released. A flexible connection 16 similar to the connection 16 in Fig. 1, connects the plunger 11 to a cap 24 which cooperates with clips in the same way as the cap 2 in Fig. 1.

The weight 23 is normally restrained by a catch 25 which is released by a magnet 26. The conductor 27 leading to the magnet 26 may be in shunt to the circuit in which the current interrupter is inserted, or it may extend to an independent circuit intended to control the current interrupter. The magnet is connected to the cap 24 and the circuit which controls the magnet is completed through the clips or other contact devices which cooperate with the cap 24.

A similar arrangement including contact springs 22 is provided at the upper end of the plunger 11 in Fig. 3. The weight 23 and connector 16 at the lower end are similar to the corresponding parts in Fig. 2. The catch 30, corresponding to the catch 25 in Fig. 2, is spring pressed to release position and is held in the illustrated position by a fusible wire 31. The conductor 32 leading to the wire 31 may be connected either to a shunt of the main circuit or to a control circuit as explained in connection with the conductor 27 in Fig. 2.

A connecting device 33 for the conductor 32 is mounted upon but insulated from the bracket 34 which extends from the cap 24. One end of the fusible wire 31 is secured by the connecting device 33 and the other end thereof is mechanically secured to the tail of the catch 30, but insulated therefrom by the insulation 35. A connection extends from the wire 31 to the bracket 34 and thus to the cap 24.

In the operation of that form of the device illustrated in Fig. 1, when the current flowing between the sleeve 3 and the cap 2 exceeds a predetermined value, the link 12 is melted at its reduced section. The spring 15 moves the plunger 11 downwardly. This motion will, however, be slow compared with speed of the separating elec-

trodes usual in circuit interrupting devices of the type in which the link is ejected. Where the link is a fine wire or strip as has been used in the past, the inertia of the link is so small that it is ejected at a high rate of speed rather than at the slow speed of the device of my invention. Preferably, this slow movement is accomplished by making the plunger 11 a thick rod of copper, thereby giving it considerable inertia, and selecting for the spring 15 one which cannot exert force enough to accelerate the heavy plunger 11 to more than a moderate speed. Preferably, these constants are so chosen that the plunger 11 will require from 3 to 10 cycles to travel the full length of its movement.

Another consequence of choosing a thick rod for the plunger 11 is that it will not yield under the gas pressure developed and, by bending, jam against the sides of the passage 8. Should the plunger jam, it might be prevented from traveling far enough to extinguish the arc. Then the arc would continue until gas enough was evolved to burst the tube.

When the fuse 12 first melts, an arc is formed within the flared or bell-shaped opening 37 of the passage 8. The current which melted the fuse 12 may have been barely sufficient to melt it, as would be the case when a small overload existed in the circuit, or it may be very much heavier than this, as would be the case when a short circuit occurred.

In the latter case, the arc which is formed between the remains of member 12 and the upper end of plunger 11 will carry a heavy current. It will, therefore, act vigorously upon the walls of the bell-shaped opening 37 and cause the rapid evolution of gas. This gas, flowing through the ionized gas in the arc itself, causes rapid extinction of the arc.

The current being an alternating current, passes through zero at each half cycle and for heavy currents it is intended that the gas generated in the first half-cycle shall be sufficient to prevent a restriking of the arc when the voltage rises again in the second half-cycle. The total quantity of gas evolved will not be very great even though the current be heavy because of the short duration of the arc. Because this arc is of short length, it acts upon only a small area of the boric acid. This is another reason why, although the current is heavy, the quantity of gas evolved is not excessive. The gas pressure built up will therefore, be insufficient to burst the tube.

The hot gases, consisting principally of water vapor, pass into the space provided by the openings in the washers 17 and 18 which, being of copper and presenting a large surface, quickly cool the water vapor. The advantage of retaining the gases within the tube and removing the pressure by cooling them is, that a flame is not produced outside of the tube when the device operates. If the situation is such that such a flame may be permitted, the cap plate 21 may be omitted and the gases permitted to escape at the top of the device. It will then be permissible to build the device of dimensions and materials which can withstand less internal pressure.

Whether the vapor moves upwardly because of condensation by the washers or because of a provision for escape to the outside atmosphere at the top of the device, the gas is directed as a blast against the arc and a turbulent mixture of ionized and non-ionized vapors results which is effective in extinguishing the arc.

When the current which melted the fuse 12 is

small, the arc generated is not capable of effectively heating the walls of the bell-shaped opening 37 because the large cross-section of the opening provides a considerable distance between the arc and the walls. Under these circumstances, as the member 11 moves under the influence of the spring 15 it causes an elongation of the arc. The lower end of the arc will then be in the passage 8 which, being of small cross-section, produces an intimate contact between the arc and the boric acid or similar material.

The quantity of gas evolved is increased because of this more effective action of the arc upon the material. The long passage through which the gases must pass to emerge into the bell-shaped opening 37 causes an even greater intermixture between the evolved gases and the ionized gases and deionization is thereby quickly effected. Even with currents barely sufficient to melt the member 12 the arc will not be rekindled after passing through zero more than a few times, because sufficient deionizing effect is produced to prevent such rekindling.

When the current is heavy, the gas is evolved quickly because the energy of the arc is so great that, even while it acts upon a very short and wide part of the passage, it delivers enough energy thereto to evolve the needed amount of gas within one half-cycle.

When the current is small, the gas is more slowly evolved because less power is available. Yet the arc in this case is of considerable length and so acts upon a considerable area of the boric acid. Moreover, in this case the walls being closer to the arc are acted upon more effectively. The evolved gas in this case must pass through a greater length of arc to reach the mouth of the tube. It is thereby more effectively mixed with the ionized gas and so more effectively hastens deionization.

These circumstances sufficiently overcome the slower evolution of the gas to largely deionize the interior of the passage. Then when the current passes through a zero value, the rise of voltage in the next half-cycle will not rekindle the arc.

The slow evolution of the gas permits more time for the condensing action of the washers 17 and rings 18 to relieve the pressure or for passage of gas through the end of the tubes if left open. Thus, even if slightly more gas should be evolved with arcs of small currents, the gas pressure will not rise above that generated by an arc which is extinguished during the first half-cycle.

I find therefore that a tube with sufficient mechanical strength to withstand the pressure developed by an arc of heavy current during one half-cycle will suffice for the whole range of current values.

By making the motion of the member 11 too slow to draw a heavy arc into the restricted portion of the passage within a half-cycle, I ensure that a heavy-current arc is never in position to act upon a large area of closely adjacent material and so avoid the development of dangerous pressures because after the half-cycle has elapsed the heavy arc has been extinguished.

For arcs of intermediate current strength, the quantities discussed above are of intermediate value but in no instance does the resultant gas pressure rise above that just stated.

In the form shown in Fig. 2, the plunger can be released by sending a current through the conductor 27. This current may be derived by a shunt from the current through the circuit to be

protected and may, therefore, be proportional to the main current. If desired, however, the conductor 27 may be supplied with current from an independent source and energized when it is desired to operate the circuit interrupter.

When the magnet 26 is energized it moves the hook 25 and releases the weight 23. The plunger 11 is then moved downwardly by the motion of the weight. The acceleration which it thus receives is in no case (materially) greater than that due to the action of gravity upon the weight 23. The plunger 11 being rigid cannot buckle under the influence of the gas pressure and afford a stoppage for the passage 8. Moreover, the gas pressure against the upper end of the plunger is small compared to the action of gravity upon the mass 23 and will not materially accelerate the movement. It is therefore assured that the plunger 11 will never move downwardly fast enough to bring the arc, corresponding to a heavy current, into the narrow part of the passage 8. This prevents evolution of an undesirably large quantity of gas with the accompanying danger of bursting the tube.

In the structure shown in Fig. 3, current through the conductor 32 may be either from a shunt or from a separate control circuit. When this current exceeds a predetermined value, the fusible wire 31 is melted, with the result that the catch 30 moves under the action of its spring 30 and releases the weight 23. The operation of this form of device thereafter is exactly like that for the form shown in Fig. 2.

When the device shown in Fig. 1 has operated, it may be restored to original condition by replacing the fused member 12. I have found the most convenient method of doing this is to supply a new rod 11 with a member 12 attached thereto. The repair man will detach the old member 11 from the disk 14 and attach the new one in its place. Then by compressing the spring 15 the new member 12 is brought into its place and is secured there by the screw 13.

In the form shown in Fig. 2, it is only necessary to push up the weight 23 and the catch 25 automatically engages it. In the form shown in Fig. 3, the fuse wire 31 must be replaced after the weight 23 has been raised and the catch 30 forced into engaging position.

In all three forms, each operation of the device enlarges the passage 8 by destroying some of the boric acid. The devices may not be used more than a limited number of times for this reason. After that the packed material must be renewed.

In Fig. 1 the relation between the stiffness of the spring 15 and the inertia of the rod 11 must be correctly chosen to give the proper speed to the movement of the rod. In Figs. 2 and 3 the combined mass of the weight 23 and the rod 11 must be so chosen that the combined effect of gravity and gas pressure shall give the proper speed to the rod. The arc-current goes through zero each half-cycle. During the next half-cycle the voltage rises and if the length of the gap has not become too great the arc will be rekindled. If the motion of the rod 11 is too slow this will happen notwithstanding the evolved gas. On the other hand if the movement of the rod 11 is too rapid the arc corresponding to a strong current will be elongated into the passage 8 so far before the current reaches its zero value in the first half-cycle that the area of contact between arc and boric acid will be too great and there will be evolved enough gas to burst the tube.

I have found that two inches per cycle is about

the correct speed. At this speed the plunger will traverse its full stroke in some three or four cycles.

Many other modifications of my invention will be readily apparent to those skilled in the art and need not be specifically described. The omission of such specific description is not to be construed as a limitation. No limitation is intended unless necessitated by the prior art or indicated by the accompanying claims.

I claim as my invention:

1. In a device for interrupting alternating current, a body of material responsive to an arc to evolve an arc-destroying emanation, said body having a passage therethrough, two electrically connected members, said members being joined by fusible means for releasing one of said members, means for moving the released member along said passage, thereby separating said members to produce an arc between them, the speed of said moving member being slow enough to require more than two cycles to traverse the length of said passage.

2. In a device for interrupting alternating currents, a body of material responsive to an arc to evolve an arc-destroying emanation, said body having a passage therethrough, of a length exceeding that at which an arc can be struck in open air by the highest voltage expected in the normal use of the device, two electrically connected members, said members being joined by fusible means for releasing one of said members, means for moving the released member along said passage, thereby separating said members to produce an arc between them, the speed of said moving member being slow enough to require more than two cycles to traverse the length of said passage.

3. In a device for interrupting alternating currents, a body of material responsive to an arc to evolve an arc-destroying emanation, said body having a passage therethrough, fusible means for causing an arc, and means for causing it to be elongated in said passage, the rate of elongation being approximately two inches per cycle.

4. In an alternating current circuit interrupting device, fusible means for producing an arc, a body of material responsive to an arc to evolve an arc-destroying pressure-producing emanation, said body having a passage therein, means for elongating the arc produced by said fusible means by causing it to be drawn into said passage, said means including a movable electrode and means restraining the motion thereof to a speed which is not substantially greater than two inches per cycle.

5. In an arc-extinguishing device, a body of material responsive to an arc to evolve an emanation destructive of the arc, said body having a passage therein, an arc electrode having a fusible portion in said passage movable in the direction to elongate the arc and said passage being progressively restricted in said direction.

6. In a current-interrupting device, a body of material responsive to an arc to evolve an arc-destroying emanation, said body having a passage therein, fusible means for producing an arc and means for elongating said arc within said passage, said passage flaring toward the origin of said arc.

7. In a current-interrupting device, a body of material responsive to an arc to evolve an arc-destroying emanation, said body having a passage with a flared mouth, means having a fusible section for initially producing an arc at said mouth, means for elongating said arc within said passage.

8. In a current-interrupting device, a body of material responsive to an arc to evolve an arc-destroying emanation, said body having a passage therethrough with a flared mouth, means having a fusible section at said mouth for producing an arc at said mouth means for elongating said arc within said passage and means for restricting the flow of said emanation out of said passage at the other mouth thereof.

9. In a current-interrupting device, a body of material responsive to an arc to evolve an arc-destroying emanation, said body having a passage therethrough with a flared mouth, means having a fusible section at said mouth for producing an arc at said mouth means for elongating said arc within said passage, and means for prolonging said arc within said passage, said passage being of larger cross-section near the origin of said arc than in the region along said prolongation.

10. In a circuit interrupter, a body of material responsive to an arc to evolve a non-inflammable, readily condensable vapor, and means for causing an arc in intimate contact with different portions of said body and causing arcs of one current intensity to be finally extinguished in contact with one part of said body defining an opening of large cross-section and arcs of another current intensity to be finally extinguished in contact with another part of said body defining an opening of small cross-section.

11. In a circuit interrupter, a body of material responsive to an arc to evolve a noninflammable, readily condensable vapor, a tubular passage through said body, said passage being of a large size adjacent one end and a smaller size adjacent the other end, and means movable through said passage for drawing the arc therein, said means initially drawing the arc at the large end of said passage and later drawing the arc into the smaller end of said passage.

12. In a circuit interrupter, means of insulating material having a passage therethrough, said passage having a considerable length of substantially uniform width and having a portion which increases in width from said portion of uniform width, means for initially causing an arc at the wide portion of said passage and drawing it into said portion of uniform width.

13. In a circuit interrupter, means of insulating material having a passage therethrough, said passage having a considerable length of substantially uniform width and having a portion which increases in width from said portion of uniform width, a conducting member extending through said passage, said conducting member having a cross-section which substantially fills the portion of said passage of uniform width, and said conducting member initially causing the arc at the wide portion of said passage and being movable to draw the arc into the portion of said passage of uniform width.

14. In a fuse, means of insulating material having a passage therethrough, said passage having a portion of substantially uniform width at one end thereof and said passage increasing in width at the other end thereof and being open at said wide end, a rigid conducting member extending through said passage and having a cross-sectional area such as to substantially close the end of said passage of uniform width, said conducting member having a portion of fusible material adjacent the open wide end of said passage for causing an arc and being movable to draw the arc into the passage.

15. In a circuit interrupter, means of insulating material having a passage therethrough, the

- inner wall of said passage having portions of a material which gives off an arc extinguishing substance when acted upon by the arc, said passage having a considerable length of substantially uniform width and having a portion which increases in width from said portion of uniform width, means for initially causing an arc at the wide portion of said passage and drawing it into said portion of uniform width.
- 10 16. In a fuse, means of insulating material having a passage therethrough, the inner wall of said passage having portions of a material which gives off an arc extinguishing substance

when acted upon by the arc, said passage having a portion of substantially uniform width at one end thereof and said passage increasing in width at the other end thereof and being open at said wide end, a rigid conducting member extending through said passage and having a cross-sectional area such as to substantially close the end of said passage of uniform width, said conducting member having a portion of fusible material adjacent the open wide end of said passage 10 for causing an arc and being movable to draw the arc into the passage.

HERBERT L. RAWLINS.
